VAT LIFTING AND DUMPING TRUCK

Irvin F. Schreck, South Euclid, Ohio

Application June 17, 1953, Serial No. 362,274

12 Claims. (Cl. 214—313)

This invention relates to a method of and apparatus for hoisting, transporting and tilting barrel-like containers. 15

The method of the present invention may be used to handle various types of barrel-like containers but is preferably used to handle barrels or vats having a centrally bulged portion of circular cross section. In this method an expandable and contractible annulus is supported concentric to and above the barrel to be lifted. The internal diameter of the annulus is normally such that the annulus may be slid down over the bulge of the barrel. The annulus is moved down from its position above the barrel to a position a short distance below the bulge, and the annulus is then contracted so that the internal diameter is less than the diameter of the bulged portion of the barrel. When the barrel is lifted the weight thereof is imposed upon the contracted annulus so that a substantially uniform pressure is applied to the entire circumference of the barrel whereby gripping pressures tending to distort the barrel are avoided and the barrel may be transported and tilted to discharge its contents without damaging the barrel.

The apparatus for performing the above-mentioned method preferably comprises an industrial lift truck having a carriage mounted for movement vertically on upright guide standards attached to the truck frame. An annulus is carried on the carriage for tilting movement about a horizontal axis preferably by horizontal trunnions supported by a pair of spaced cantilever arms extending forwardly from the carriage. In order to provide a cushion between the annulus and the barrel being lifted, it is desirable to employ a rubber ring between said annulus and said barrel. To decrease the internal diameter of the annulus so as to grip the barrel while at the same time providing a cushion, it is preferable to provide a hollow flexible inflatable ring, such as a hollow inflatable rubber annulus, supplied with air under pressure from the truck frame through a flexible conduit.

An object of the present invention is to provide a simple and economical method and apparatus for hoisting and tilting barrel-like containers wherein a uniform gripping pressure is applied throughout the circumference of the container by a radially contractible ring.

A further object of the present invention is to provide a method of lifting a barrel wherein a radially contractible annulus is slid down over the bulge of the barrel and the annulus is contracted so as to grip the barrel.

A still further object of the invention is to provide a slack-take-up roller for a flexible conduit conveying fluid from the frame of an industrial lift truck to the vertically movable carriage thereof.

Other objects, uses and advantages of the present invention will become apparent from the following description and drawings.

Reference should be had to the accompanying drawings forming a part of this specification, in which:

Figure 1 is a side elevation of a lift truck embodying

2

the invention, showing the inflatable gripping ring elevated to a position above and concentric to a barrel to be lifted;

Fig. 2 is a fragmentary side elevation of the lift truck showing the inflatable gripping ring supporting the barrel off the ground;

Fig. 3 is a fragmentary side elevation of the lift truck showing the inflatable gripping ring tilted to a pouring position;

10 Fig. 4 is a top plan view of the lift truck;

Fig. 5 is a front elevation of the truck partially in section;

Fig. 6 is a fragmentary side elevation of the guide standard viewed as indicated at 6—6 in Fig. 5;

Fig. 7 is a fragmentary horizontal section taken on the line indicated at 7—7 of Fig. 5;

Fig. 8 is a fragmentary vertical section through the deflated gripping ring taken on the line indicated at 8—8 in Fig. 1;

Fig. 9 is a fragmentary vertical section through the inflated gripping ring taken on the line indicated at 9—9 in Fig. 4; and

Fig. 10 is a diagrammatic view showing the fluid systems and the fluid connections from the truck frame to the tilting motor and the inflatable rubber ring.

Referring more particularly to the accompanying drawings, the industrial lift truck of the present invention has a frame which includes a horizontal base member 1 provided with a rear portion 2 and a forward portion formed by a pair of laterally spaced side members 3 and 4. A pair of aligned laterally spaced front supporting wheels 5 and a pair of laterally spaced stops 6 are carried by the side members 3 and 4. A rear steering and driving wheel 7 is mounted in a frame 8 swiveled in the rear portion 2 of the base member 1. The wheel 7 is driven by means of an electric motor mounted on the frame 8 within a housing 9 and geared to the wheel 7 through a sprocket chain 10.

A draft tongue 11 is connected by a horizontal pivot 12 to the frame 8 and may be used to steer the truck while it is being propelled by the electric motor in housing 9, or to manually move the truck when said motor is idle. At the outer end of the draft tongue 11 and rigidly attached thereto are tubular hand grip members 13 which project from opposite sides of the tongue 11. If desired, suitable electric control means for the driving and hoisting means may be incorporated in the hand grip members 13, for example, the control means disclosed in my Patent No. 2,520,857, granted August 29, 1950.

The frame includes an upstanding telescopic elevator or guide standard formed by an outer vertical support 14 rigidly attached to the base member 1 and an inner vertical support 15 mounted for movement vertically with respect to the outer support 14. The outer support is formed by a pair of vertical channel guide members 16 and 17 welded at their lower ends to the base member 1 at the sides thereof and connected at their upper ends to a top cross bar 18 which joins the upper ends of the channel members 16 and 17. A horizontal shelf 19 is supported on the outer support 14 and projects rearwardly therefrom. The inner support 15 includes a pair of vertical channels 20 and 21 mounted for travel vertically with respect to the channel members 16 and 17 and also includes a top cross member 22 joining the top ends of the channels 20 and 21. These channels carry two vertically spaced pairs of laterally aligned rotatably mounted rollers 23 and 24 which engage the inwardly projecting flanges of the channel members 16 and 17 and are guided vertically thereby.

A load supporting carriage 25 is mounted for travel vertically on the inner support 15 of the upstanding

elevator standard and is provided at its forward end with a pair of aligned, laterally spaced cantilever arms 26 and 27 and at its rearward end with a flat vertically disposed plate 28 positioned between the channels. The flat plate 28 has rearwardly projecting flanges 29 that support two vertically spaced pairs of aligned, laterally spaced rollers 30 and 31 that are guided between and engage the flanges projecting from the channels 20 and 21. A reinforcing arm 32 extends between a bottom side edge of the plate 28 and the forward end of each of the arms 26 and 27 to provide a strong triangular support.

The carriage 25 is raised and lowered by means of an hydraulic cylinder 33 mounted in vertical position upon the base member 1 midway between the side posts formed by channel members 16 and 17 of the guide standard. The cylinder 33 has a vertically movable piston rod or plunger 34 that carries a pair of laterally spaced sprocket wheels 35 at its upper end. A sprocket chain 36, attached at one end to the plate 28 of the carriage 25, extends over each sprocket wheel 35 and is attached at its opposite end to the truck frame. The upper end of the plunger 34 engages the top cross member 22 of the inner support 15 to move the same vertically with the plunger. By the use of the sprocket and chain hoisting connection, the inner support 15 moves half as far as the carriage 25 during each revolution of the sprocket wheels 35. The vertically spaced pairs of rollers 23, 24, 30 and 31 and the supports 14 and 15 of the elevator standard provide a strong support for the load supported on the carriage 25 at all vertical positions of the carriage and the inner support 15. The inner support 15 is particularly advantageous where a heavy load is to be lifted a considerable distance, since it allows the use of a relatively short standard.

Immediately to the rear of the elevator standard the rear portion 2 of the base member 1 supports a battery frame 37 containing an electric battery 38 which is connected to the electric motor within housing 9 by an electrical conduit 39.

A rigid metal annulus 40 is mounted on the forward portion of the carriage 25 for rotation about a horizontal axis by aligned horizontal trunnions 41 that are journaled in upwardly extending flanges 42 welded to the top of the forwardly projecting arms 26 and 27, the trunnion axis being located a short distance in front of the center of the annulus 40 as viewed in Fig. 1. A lever arm 43 is welded to the annulus 40 at its one end and is pivotally connected to a piston rod 44 of a single-acting reciprocating tilt motor 45 at its other end. The cylinder of the tilt motor 45 is pivotally mounted on an upstanding flange 46 welded to the arm 27 at the inner end thereof. A short flexible conduit 47 is connected at one end to the intake of the motor 45 to supply motive fluid thereto while accommodating tilting movement of the motor 45 with respect to the carriage 25. The other end of conduit 47 is rigidly connected to the carriage 25 at 48. The strokes of the tilt motor 45 and the lever arm 43 are of such lengths that the annulus 40 may be tilted approximately 135° from the position shown in Figs. 1 and 2 to the pouring position shown in Fig. 3.

The metal annulus 40 is preferably of cylindrical form and includes upper and lower tubular metal stiffening rings 49 and 50 welded to the top and bottom edges thereof. An inflatable tubular rubber ring 51 is located closely adjacent the inner surface of the metal annulus 40 and between the rings 49 and 50. The tubular rubber ring 51 is normally axially elongated in cross sectional form and contains a similarly elongated annular air chamber therein whereby the inner diameter of the ring will be radially contracted when the ring is inflated as shown in Fig. 9. To prolong the life of the ring without greatly increasing the cost thereof, it is preferable to provide fabric reinforcement at least on the inner barrel-gripping surface of the rubber ring. As herein shown the ring 51 has a substantially cylindrical fabric rein-

forced inner rubber surface 52. It is often desirable to support the rubber ring 51 from the top of the metal annulus 40. As herein shown, strap slots 53 are provided in the top of the annulus 40 just below the upper ring 49 to receive a plurality of flexible fabric reinforced supporting straps 54 which extend from within the rubber ring 51 over the top of the upper ring 49, through the slots 53, and along the inner surface of the annulus 40. The two ends of each strap 54 are connected together by suitable fasteners 55. A short flexible conduit 56 is rigidly connected at one end to the metal annulus 40 and at the other end to a rigid pipe 57 fixed to the top of plate 28. The conduit 56 accommodates tilting movement of the annulus 40 with respect to the carriage 25 while conveying air to inflate and deflate the ring 51.

The horizontal shelf 19, which is supported on the guide standard of the truck frame, provides a support for an air compressor 58 that is driven by an electric motor 59 and for a pair of housings 60 and 61 and their associated electric motors 62 and 63. The housing 60 provides a reservoir for hydraulic fluid and contains a pump 64 driven by the motor 62 for supplying motive fluid to the tilt motor 45. A supply conduit 65 conveys hydraulic fluid from the pump 64 through a two-way valve 66 to a conduit 67 which is rigidly connected at 68 to the guide standard of the truck frame near the plane of the shelf 19. Connected between the end 68 of conduit 67 and the end 48 of conduit 47 is a long flexible conduit 69 which conveys motive fluid to the tilt motor while permitting relative movement of the carriage 25 and the shelf 19. The valve 66 has a first position in which fluid is supplied from conduit 65 to conduit 67 and a second position as shown in Fig. 10 in which fluid is exhausted from conduit 67 through a bypass conduit 70.

The housing 61 is similar to the housing 60 in that it acts as a reservoir and contains means including a pump driven by the electric motor 63 for supplying hydraulic fluid under pressure to cylinder 33 to raise and lower the plunger 34. The hoisting system employed on the lift truck of the present invention may be of the type described in the aforesaid Patent No. 2,520,857.

The air compressor 58 supplies air under pressure through a supply conduit 71 and a two-way air valve 72 to a conduit 73 which is rigidly connected at 74 to the guide standard of the truck frame near the plane of the shelf 19. A long flexible conduit 75 is connected between the rigid conduit connections at 57 and 74 to convey air to and from the rubber ring 51 while permitting relative movement of the carriage 25 and the shelf 19. The two-way valve 72 has a first position wherein air under pressure is conveyed from supply conduit 71 to the flexible conduit 75 and a second position as shown in Fig. 10 wherein air is exhausted to atmosphere from the flexible conduit 75.

The long flexible conduits 69 and 75 are preferably of about the same length and have loop portions that pass beneath a pair of similar slack take-up rollers 76 and 77 which are supported in the loops of said conduits and which are provided with annular circumferential recesses that receive the flexible conduits. The rollers 76 and 77 are guided vertically by a pair of similar roller guide channel 78 and 79, the inwardly projecting flanges of which provide guiding surfaces which engage the rollers. Channels 16 and 78 and channels 17 and 79 are fixed to the frame member 1 and are spaced apart a distance only slightly greater than the width of the rollers 76 and 77, respectively, so as to provide a vertical guiding means of rectangular cross-sectional form in which the rollers may roll. The weight of the rollers 76 and 77 biases the long flexible conduits 76 and 69 in the downward direction to take up the slack caused by movement of the carriage 25 with respect to the shelf 19 of the truck frame.

The lift truck described above is usually employed

for hoisting, moving and dumping vats, hogsheads, or large barrels of the type shown in Figs. 1 to 3. Fig. 1 shows a centrally bulged barrel or vat 80 of circular cross section containing a large volume of liquid, the maximum diameter of the barrel at the bulge thereof being slightly less than the normal diameter of the expanded inner surface 52 and larger than the diameter of the contracted inner surface 52. The annulus 40 and ring 51 may obviously be made of various sizes to handle different types of vats and hogsheads.

The method of the present invention comprises placing the inflatable rubber ring 51 above and coaxial with the barrel 80 as shown in Fig. 1, sliding the ring down over the bulge of the barrel to the dotted line position shown in Fig. 1, and radially contracting the inner barrel-gripping surface of the ring 51 and raising the ring so that the internal surface 52 engages and grips substantially the entire circumference of the barrel 80 below its bulge. The barrel may be raised to any desired height as shown in Fig. 2 while the uniform gripping pressure is maintained throughout the circumference of the barrel. According to the method of the present invention the ring 51 is tilted about a horizontal axis as shown in Fig. 3 to discharge the contents of the barrel 80. Thereafter, the barrel may be tilted back to its horizontal position and lowered to the ground. The internal surface of the ring 51 is expanded to its normal diameter to release the grip on the barrel and to permit sliding of the ring upwardly over the bulge of the barrel 80.

The preferred apparatus for performing the method is the industrial lift truck described above which carries the tiltable ring 51. Before the barrel 80 is lifted carriage 25 is elevated and the rubber ring 51 is positioned above and coaxial with the barrel 80. To facilitate centering of the barrel 80 with respect to the rubber ring 51, it is preferable to employ the positioning means 6 of the side members 3 and 4. The barrel-engaging outer surfaces of the positioning stops 6 are located at predetermined equal distances from the vertical axis of the rubber ring 51 so as to locate the lift truck in proper lifting position when they engage the barrel 80. The ring 51 is slid down over the bulge of the barrel after the valve 70 is placed in the exhaust position shown in Fig. 10 to deflate the ring. Valve 72 is then moved to a position wherein conduit 71 is connected to conduit 73. A relatively low predetermined initial pressure, for example 10 to 15 p. s. i. is supplied to the ring 51 to inflate the same as shown in Fig. 9, to reduce its internal diameter, and to supply sufficient air to the rubber ring 51 to support the barrel, thereby providing a uniform gripping pressure throughout the entire circumference of the barrel. The carriage is then elevated to the desired height, and the barrel is transported horizontally by the driving wheel 7 to the desired location.

The valve 66 may be placed in a position blocking flow to and from the tilt motor 45 during hoisting and lateral moving of the barrel 80 to prevent undesirable tilting. However, the center of gravity of the barrel is preferably located a short distance behind the trunnion axis at 42 so that the piston may be held in retracted position and the barrel held horizontal as shown in Fig. 2 by the weight of the barrel alone. After the barrel has been moved to the desired location, the valve 66 is moved to a position connecting conduit 65 to conduit 67. Pump 64 then supplies hydraulic fluid through the conduits 65, 67, 69 and 47 to the motor 45 so as to tilt the barrel 80 to a pouring position and discharge its liquid contents. The annulus 40 may be tilted about 135° from the position shown in Fig. 2 to the position shown in Fig. 3 so as to provide a pouring angle of approximately 45°. The barrel is tilted back to its original horizontal position by turning valve 66 to the exhaust position as shown in Fig. 10. The weight of the barrel causes the piston rod 44 to retract, and therefore the motor 45 need not be of the double-acting type. The barrel may be released

by moving valve 72 to the exhaust position shown in Fig. 10 so as to permit sliding of the ring 51 upwardly over the bulge of the barrel 80 to the original position shown in Fig. 1.

5. It is to be understood that in accordance with the provisions of the patent statutes, variations and modifications of the specific devices herein shown and described may be made without departing from the spirit of the invention. What I claim is:

10. 1. In an industrial lift truck for hoisting and tilting barrels including a frame provided with a standard, a carriage mounted for movement vertically on the standard and having a pair of laterally spaced horizontally extending arms, and motor means to raise and lower said carriage and said spaced arms, the improvement which comprises: a tiltable barrel-receiving annulus having trunnions journaled horizontally in said spaced arms, a hollow tubular rubber ring normally of axially elongated cross-sectional form supported within and concentric with said annulus, the outer surface of said rubber ring being closely adjacent the inner surface of said annulus, said ring having a fabric-reinforced barrel-gripping inner surface of a diameter when uninflated to slip over a barrel to be lifted, means located on said frame for inflating the rubber ring to reduce the internal diameter of said rubber ring to grip the barrel, and motor means connected to said carriage to tilt said annulus about the axis of said trunnions so as to discharge the contents of the barrel supported on said carriage.
15. 2. In a barrel hoisting industrial lift truck including a frame, a standard vertically supported on the frame, a carriage mounted for movement vertically on the standard, and means to raise and lower said carriage, the improvement which comprises: a radially expandible and contractible barrel-gripping ring mounted on said carriage to tilt about a horizontal axis, means to tilt said ring about said horizontal axis, means to increase and decrease the internal diameter of said ring, and positioning means located on the lower part of said frame below said carriage and having two laterally spaced barrel-engaging stops for engagement with a barrel to be lifted to center said ring with respect to the barrel.
20. 3. In a barrel hoisting and tilting industrial lift truck including a frame, a guide standard vertically supported on the frame, a carriage mounted for vertical movement on the guide standard, and means to raise and lower said carriage, the improvement which comprises: a rigid annulus having horizontal trunnions journaled in said carriage, said annulus having a flexible radially contractible interior face normally of a diameter to slip downwardly over the widest portion of an upright barrel to be lifted, means to reduce the internal diameter of said interior face to cause said face to engage the barrel throughout its circumference when the carriage is elevated, and means to tilt said annulus and the barrel supported thereby about the horizontal trunnion axis to discharge the contents of the barrel while the carriage is elevated.
25. 4. In a material handling industrial lift truck including a frame provided with a standard, a carriage mounted for movement vertically on the standard, and means to raise and to lower said carriage, the improvement which comprises: a forwardly projecting support on said carriage, article-gripping means including an inflatable flexible member carried by said support, a flexible conduit leading from said frame to said inflatable member, means located on the frame to supply fluid under pressure to said inflatable member through said conduit, a slack-take-up roller beneath which said flexible conduit passes, and a roller guide connected to said standard, said roller moving vertically on said guide to take up slack in said flexible conduit due to movement of said carriage vertically.
30. 5. The apparatus defined in claim 4 wherein said inflatable member is mounted for tilting movement on said support, a fluid motor means on said carriage tilts

75

said inflatable member, and a flexible supply conduit rigidly fixed at one end to said frame and at the other end to said fluid motor means supplies fluid to said motor means from a source of pressurized motive fluid located on said frame, and wherein said standard has roller guide means connected thereto and slack-take-up roller means movable vertically on said guide means, said supply conduit passing beneath said roller means and being forced downwardly thereby so that slack in said supply conduit due to vertical movement of the carriage is taken up by said roller means.

6. In an industrial lift truck including a frame provided with a guide standard, a carriage mounted for movement vertically on the standard, and means to raise and to lower said carriage, hoisting and tilting apparatus comprising: a forwardly projecting load carrying member pivotally mounted on said carriage, fluid motor means interposed between said carriage and said member to tilt said member and having a fluid inlet connection fixed to said carriage, a source of motive fluid fixed to said frame, a flexible supply conduit rigidly connected at one end to said motive fluid source and at the opposite end to said inlet connection, said flexible conduit supplying motive fluid from said source to actuate said motor means, a vertically extending roller guide connected to said standard, a slack-take-up roller mounted for vertical movement by gravity along said roller guide, said conduit passing beneath and engaging the lower surface of said roller, said roller biasing said conduit in the downward direction to take up slack caused by vertical movement of the carriage and the fluid motor means carried thereby.

7. In a barrel hoisting industrial lift truck having a frame provided with a standard, a carriage mounted for movement vertically on the standard, and means to raise and lower said carriage, the improvement which comprises: a forwardly projecting supporting member on said carriage, a barrel-gripping hollow tubular inflatable flexible member normally of axially elongated cross-sectional form mounted along the inside surface of said supporting member to tilt about a horizontal axis and when deflated adapted to be inserted over the top of a barrel to be lifted, means to inflate said flexible member to reduce the internal diameter thereof, said means causing the inflated flexible member to act as a cushion and to exert a uniform gripping pressure throughout the major portion of the circumference of the barrel when said carriage and said barrel are elevated, and means to tilt said flexible member and the barrel supported thereby about said horizontal axis.

8. Apparatus for hoisting a barrel-like container comprising: a rigid circumferentially continuous annulus having a metal ring fixed to the top thereof and a cylindrical inner surface, an inflatable hollow tubular rubber ring normally of axially elongated cross-sectional form having a circumferentially continuous fabric-reinforced inner portion adapted to grip said container when inflated, a plurality of fabric-reinforced flexible straps each extending over said metal ring and closely adjacent said cylindrical inner surface, each of said straps surrounding said rubber ring and holding said rubber ring adjacent said inner surface, and means for inflating said rubber ring and lifting said barrel, said rubber ring applying a uniform pressure throughout the circumference of said container.

9. In a barrel hoisting industrial lift truck including a frame, a standard supported vertically on the frame, a carriage mounted for movement vertically on the standard and having a pair of laterally spaced horizontally

extending cantilever arms, and motor means to raise and lower said carriage, the improvement which comprises: a circumferentially continuous annulus having trunnions mounted horizontally in said spaced arms, means connected to said carriage to tilt said annulus about the trunnion axis, a circumferentially continuous inflatable tubular rubber ring supported within and concentric to said annulus, said ring being normally of axially elongated cross-sectional form, and means to inflate and deflate said rubber ring to reduce and increase, respectively, the diameter of its internal surface.

10. In a barrel hoisting industrial lift truck including a frame, a standard supported in upright position on the frame, a carriage mounted for movement vertically on the standard, and motor means to raise and lower said carriage, the improvement which comprises: a rigid annulus having horizontally aligned trunnions mounted in said carriage, means for tilting said annulus about the trunnion axis, a hollow tubular inflatable flexible ring supported within and concentric to said annulus and normally of a size to slip downwardly over the widest portion of an upright barrel to be lifted, means to inflate said flexible ring to reduce the internal diameter thereof to less than the diameter of said widest portion and to cause said ring to exert a uniform gripping pressure throughout the circumference of the barrel when said carriage and said ring are elevated to lift the barrel, and means to tilt said annulus and the flexible ring carried thereby about said horizontal trunnion axis to dump the barrel.

11. Apparatus for hoisting and transporting an upright centrally-bulged barrel comprising a vertically movable carriage, a radially contractible ring mounted on said carriage to swing about a horizontal axis, said ring normally having an internal diameter greater than the maximum diameter of the bulge, means for lowering said carriage and the ring supported thereby from a position where the ring is above and coaxial with the barrel to a position where the ring is below the bulge of said container, means for radially contracting said ring so that its internal diameter is less than the diameter of said bulge and its internal surface engages substantially the entire circumference of said barrel below said bulge when the ring is lifted, means for elevating said carriage to lift said ring and the barrel supported thereby, and means for tilting said ring and said barrel about said horizontal axis to discharge the contents of the barrel.

12. In a barrel hoisting and tilting industrial lift truck including a frame having an upright guide standard, a carriage mounted for vertical movement on the guide standard, and means to raise and lower said carriage, the improvement which comprises: a forwardly projecting support rigidly mounted on said carriage, a hollow tubular inflatable rubber ring mounted on said support to swing about a horizontal axis to a horizontal position, means for inflating and deflating said rubber ring to grip and release a barrel, means for limiting the radial expansion of the exterior circumferential portion of said ring, and means for tilting said ring whereby a barrel may be lifted and tilted to discharge its contents.
